CLOSURE FOR COLLAPSIBLE TUBES

Duane C. Maddux, Highland Park, Ill.

Application March 9, 1938, Serial No. 194,946

13 Claims. (Cl. 221—60)

My invention relates to closures for collapsible tubes, and deals more particularly with an improvement over the structure patented by John Lacher on February 6, 1934, under No. 1,945,612.

5 One object of the improvement is to construct a closure in one piece, whereby to save material in its production and labor in its application.

A further object of the improvement is to provide a resilient clamp which is limited to the zone 10 in which the dispensing of the material in the tube occurs.

Another object of the invention is to construct the improved closure with clamping elements which are adjustable to vary the pressure exerted 15 on the tube in the zone of discharge.

An additional object of the invention is to provide a pair of clamping elements which apply a uniform pressure at all points in the zone of discharge, whereby to render the ribbon of material 20 dispensed even and firm however thin it may be.

A further object of the invention is to design the novel closure with clamping means which are identical on both sides of the tube and situated to apply equal pressure on such sides.

25 With the above objects in view, and any others which may suggest themselves from the description to follow, a better understanding may be had of the improved closure by reference to the accompanying drawing in which,—

30 Fig. 1 is an elevation of a collapsible tube equipped with the novel closure;

Fig. 2 is a magnified side view of the lower portion of Fig. 1;

Fig. 3 is a view similar to Fig. 2 but in cross- 35 section;

Fig. 4 is a magnified bottom plan view;

Fig. 5 is an enlarged plan view of the blank from which the closure is formed; and

Fig. 6 is a magnified duplication of the lower 40 portion of Fig. 1.

While the patent previously referred to deals with a tube which requires closures to be formed at both ends, late developments in collapsible tube manufacture provide a tube of the type indicated in Fig. 1 of the drawing, which is pressed as a cylindrical cup 10 with a circular closed end 11 at one end, so that such end requires no further attention before the tube is filled. Thus, it remains only to apply a closure to the opposite 45 or open end of the tube after the same has been filled.

As in the previous instance, the open end of the tube is pressed flat from the sides, as indicated at 12 and 13, whereby to provide a substantially rectangular base over which to mount

the closure. The latter is in the form of a U-shaped clip 14 which is formed from the blank indicated in Fig. 5.

The blank of Fig. 5 is a thin sheet of springy metal, and the dotted line 15 indicates where it is folded into the U form, this fold of course being so close as to make a snug sliding fit when the clip is closed upon the assembled ends 12 and 13 of the tube. The blank is stamped with four substantially triangular openings 16 to define sloping sides 17, medial bars 18 and cross-heads 19 at the inner ends of the latter. The sides 17 are spaced somewhat from the ends of the cross-heads 19 as indicated at 20; and the cross-heads are spaced from each other a slight 15 distance as indicated at 21.

After the blank of Fig. 5 has been folded on the line 15, the cross-heads 19 lie closely side by side, while the doubled sides 17 are somewhat spaced from the ends thereof. However, the 20 forming operation also includes the arching of the intermediate outer sections 22 of the blank in outward directions, as indicated particularly in Fig. 4, the effect of this action being to gather the sides 17 into contact with the ends of the 25 doubled cross-heads 19, as shown in Fig. 1.

The arching of the sections 22 carries the bars 18 outwardly from the sides of the folded clip, separating the cross-heads 19 from each other. The final forming operation therefore deflects 30 the cross-heads inwardly to meet at the bottom.

After the clip has been applied to the end of the tube by means of a press, it will firmly cling or hold to the same. With the tube containing a filling of a plastic substance, such as dental 35 cream, shaving cream, cement, etc., the weight of the filling would ordinarily cause those portions of the tube walls which are opposite the sections 18 and 22 of the clip to expand and seat in such sections; or, the slight initial pressure of 40 the tube when it is handled or about to be used will suffice to accomplish the same action. However, increased pressure will cause the walls of the tube to bear against the sections 18 and 19 sufficiently to separate those on one side of the 45 tube from the ones on the opposite side, creating a fissure between the tube ends along the course of the sections 19, by way of which a thin ribbon of the plastic substance will emerge from the tube.

As originally constituted, the assembly appears in cross-section as in Fig. 3, which clearly shows that the doubled end of the tube has expanded or assumed the form of the sections 18 and 19, so that the tube walls seat therein. Thus, the 50

meeting ends of the sections 19 have become slightly separated, although the folds 17 of the clip provide bottom retainers to securely hold together so much of the tube walls as occurs between such folds providing an end closure for such walls.

The deflecting angle of the sections 19 is imparted to apply constant pressure from the clip upon the tube walls to keep them closed at the outlet, that is, between the sections 19. With the angle of deflection shallow, the pressure of the plastic material—when the same is dispensed—is generally in an outward direction, readily procuring the separation of the sections 19. Thus, the ribbon dispensed is fairly thick. However, if a thinner ribbon is desired, the angle of deflection for the sections 19 is made more pronounced. In this case a lesser area is had for transmitted pressure in a lateral direction, and the tendency is therefore greater for the sections 19 to cling in the closed state. Therefore they will yield only slightly, permitting but a very thin ribbon to issue from between the two walls in their zone. It is understood that a ribbon of the character dispensed from a tube of the above nature is quite thin even in its heaviest form, so that its further attenuation by the process just described is between slight limits. It is therefore possible to form the clip when folded or applied to suit different requirements of material ribbon thickness, as governed by the consistency of the material, the amount ordinarily dispensed, the surface to be covered or any other incidental considerations.

It will be evident from the above description that I have provided a closure for the purpose specified which is a radical improvement over the one previously considered. First, it is made of a single piece of material. Second, the material is springy metal, so that it is capable of assuming tension without the need of springs or other additional elements. Further, the belt-like bands 22 in which the walls of the tube expand near the bottom provide an integral and medial bar or lever 18 on each side against which tube pressure is exerted during the dispensing action, rendering such pressure centralized and balanced between the sides of the tube. Further, the cross-heads 19 are carried by the medial sections 18 like T-heads, receiving their stress from the center and distributing the same evenly across the dispensing zone. Further, the sections 18 and 19 are in a single piece and therefore easily adjusted as to relative angle by machine, or even by hand, if the feed is desired to be changed. Altogether the integral and compact nature of the clip enables it to maintain its hold firmly; and its stiff and springy property causes it to resist deforming and weakening strains which may prejudice the uniformity of the feed or alter the firm and even character of the material ribbon as it is dispensed.

While I have described the novel improvement along more or less specific lines, various minor changes or refinements may be made therein without departing from its principle, and I desire to consider all such minor changes and refinements as coming within the scope and spirit of the appended claims.

I claim:—

1. A dispensing closure for collapsible tubes comprising a U-shaped metal clip adapted to receive in its fold the flattened terminal wall portions of a tube, said clip having an opening

adjacent the medial zone of said wall portions, and parts of the clip serving in said zone as clamps for the wall portions to normally keep them in closed contact.

2. The structure of claim 1, said parts being constituted to become tensioned by the separation of the wall portions.

3. The structure of claim 1, said parts being adjustable to positions imparting different degrees of tension from the separation of the wall portions.

4. The structure of claim 1, the clip being of spring material, whereby to render said parts capable of tension on the separation of the wall portions.

5. The structure of claim 1, the clip having band portions along courses substantially parallel to its fold, and said parts comprising extensions of such band portions.

6. The structure of claim 1, the clip having band portions along courses substantially parallel to its fold, and said parts comprising extensions of such band portions in the direction of the fold.

7. The structure of claim 1, the clip having band portions along courses substantially parallel to its fold, and said parts comprising extensions of such band portions in the direction of the fold and terminating therat.

8. A dispensing closure for collapsible tubes comprising a U-shaped metal clip adapted to receive in its fold the flattened terminal wall portions of a tube, said clip having its fold interrupted opposite the medial outlet zone of said wall portions, the clip having band portions along courses substantially parallel to its fold, and extensions of said band portions formed to fill the space of interruption in the fold, such extensions serving in said zone as clamps for the wall portions to normally keep them in closed contact.

9. The structure of claim 8, said extensions being directed from the middle of the band portions to points approximately in line with the fold.

10. The structure of claim 8, said extensions being bars directed from the middle of the band portions and enlarged with cross-heads filling the interruptions in the fold and extending to points approximately in line with the same.

11. The structure of claim 8, the band portions being outwardly arched from the planes of the clip sections, said extensions being bars directed from the middle of the band portions and spaced accordingly from the planes of the related clip sections, and the bars being enlarged with inwardly deflected cross-heads filling the interruptions in the fold and extending in converging relation to points in line with the same.

12. The structure of claim 8, the band portions being outwardly arched from the planes of the clip sections, said extensions being bars directed from the middle of the band portions and spaced accordingly from the planes of the related clip sections, the bars being enlarged with inwardly deflected cross-heads filling the interruptions in the fold and extending in converging relation to points in line with the same, and the cross-heads being adjustable to different angles for changes of tension therein in response to the separation of the wall portions.

13. The structure of claim 1, said clip being in one piece.

DUANE C. MADDUX.
